Primary Examiner — Mary Ann Calabrese*Assistant Examiner* — Catherine Ho(74) *Attorney, Agent, or Firm* — Knobbe, Martens, Olson & Bear LLP(57) **CLAIM**

We claim the ornamental design for a bar, as shown and described.

DESCRIPTION

FIG. 1 is a top, front, and left side perspective view of a bar showing our design;

FIG. 2 is a front elevation view of the design;

FIG. 3 is a rear elevation view of the design;

FIG. 4 is a left-side elevation view of the design;

FIG. 5 is a right-side elevation view of the design;

FIG. 6 is a top plan view of the design;

FIG. 7 is a bottom plan view of the design; and,

FIG. 8 is a bottom, front, and right side perspective view of the design.

The broken lines shown in the figures represent portions of the bar that form no part of the claimed design.
